UNITED STATES PATENT OFFICE.

FRANK VAN ALSTINE, OF SACRAMENTO, CALIFORNIA.

LAWN EDGER.

Application filed May 11, 1925. Serial No. 29,385.

To all whom it may concern:

Be it known that I, FRANK VAN ALSTINE, a citizen of the United States, residing at Sacramento, county of Sacramento, State 5 of California, have invented certain new and useful Improvements in Lawn Edgers; and I do declare the following to be a full, clear, and exact description of the same, reference being had to the accompanying drawings, and to the characters of reference marked thereon, which form a part of this 10 invention.

This invention relates to improvements in lawn trimming implements, and particularly 15 to one by means of which grass spreading over the edges of side-walks, drive-ways, or the like, may be quickly and efficiently trimmed along the proper edge line without the use of hand operated clippers.

20 The principal object of my invention is to provide a device of this character having a cutting disc, and a bearing and handle means therefor, so arranged that one side of the disc is entirely free from any projections or obstructions whose presence would restrict and lessen the range of usefulness of the implement.

Another object is to provide a very compact, light but substantial structure and one 30 that will be inexpensively manufactured and yet present a neat and workmanlike appearance.

These objects I accomplish by means of such structure and relative arrangement of 35 parts as will fully appear by a perusal of the following specification and claim.

In the drawings similar characters of reference indicate corresponding parts in the several views:

40 Fig. 1 is a side elevation of my improved edger.

Fig. 2 is a cross section of the same.

Referring now more particularly to the characters of reference on the drawings, the 45 numeral 1 denotes a handle of suitable length and preferably made of wood.

Fixed on one side of the handle at the lower end thereof and projecting therebeyond in longitudinal alinement therewith is 50 a support or hanger 2. This member is preferably formed of a piece of strap iron, bent outwardly of the handle onto itself

from its outer end for a certain distance as shown at 3. This member is rigidly secured to the handle by bolts 4 or the like. 55

Disposed adjacent the inner face of the member 2, that is that face thereof adjacent the handle 1, is a roller 5 of suitable diameter and width. This roller is mounted onto the member 2 by a spindle in the form 60 of a bolt 6, on which the roller turns.

The bolt has a head 7 on its outer end which is completely sunk in a socket 8 provided in the outer face of the roller. The opposite end of the bolt, from the inner face 65 of the support outwardly thereof, is of reduced size so as to provide a shoulder as at 9 on the bolt which abuts against the support and prevents the head 7 from pinching the roller and keeping the same from free 70 rotation. A nut 10 on the bolt outwardly of the support clamps the bolt securely to said support against movement relative thereto.

Abutting against the face of the roller 75 opposite to the support is a cutter disc 11. This disc is of course larger than the roller which thus forms the hub of the disc, the relative sizes of these two members determining the depth below the surface to which the device may operate. The disc is fixed onto the roller by rivets 12 or the like which are countersunk both in the disc and the roller so that the opposite faces of both these 80 members remain flush throughout. The disc has a central orifice 13 through which the head 7 may be manipulated and a lubricant applied to the spindle.

This head, as before stated, being completely sunk into the roller, it is therefore 90 entirely clear of the outer face of the disc.

The longitudinal plane of the handle 1 is between the disc and the support 2, so that the outer face of the cutter is in an entirely 95 clear and unobstructed plane. The device may therefore be operated as close to any rigid exterior projection as may be necessary without interference.

From the foregoing description it will be readily seen that I have produced such a 100 device as substantially fulfills the objects of the invention as set forth herein.

While this specification sets forth in detail the present and preferred construction

of the device, still in practice such deviations from such detail may be resorted to as do not form a departure from the spirit of the invention, as defined by the appended claim.

Having thus described my invention what I claim as new and useful and desire to secure by Letters Patent is:

A lawn edger comprising a disc, a hub secured thereto only on one side of the same,

a spindle on which the hub is turnable, a support in which one end of said spindle is fixed disposed adjacent that face of the hub opposite to the disc, a head on the opposite end of the spindle countersunk in the hub, and a handle secured to the support and disposed in a plane between the support and disc. 15

In testimony whereof I affix my signature.
FRANK VAN ALSTINE.
